UNITED STATES PATENT OFFICE.

CHARLES TROUP, OF WATSEKA, ILLINOIS.

SWITCH AND SIGNAL.

No. 812,102.

Specification of Letters Patent.

Patented Feb. 6, 1906.

Application filed September 30, 1905. Serial No. 280,738.

To all whom it may concern:

Be it known that I, CHARLES TROUP, a citizen of the United States, residing at Watseka, in the county of Iroquois and State of Illinois, have invented certain new and useful Improvements in Switches and Signals, of which the following is a specification.

This invention relates to safety appliances for railways, being designed to combine with a switch and signal a lock and operating means of novel formation whereby it is practically impossible to throw the signal to "safety" until the switch is wholly closed, thereby preventing the casualties attributable to an open or misplaced switch.

For a full description of the invention and the merits thereof and also to acquire a knowledge of the details of construction of the means for effecting the result reference is to be had to the following description and accompanying drawings.

While the invention may be adapted to different forms and conditions by changes in the structure and minor details without departing from the spirit or essential features thereof, still the preferred embodiment is shown in the accompanying drawings, in which—

Figure 1 is a plan view of a railway-switch and operating mechanism embodying the invention. Fig. 2 is an elevation thereof. Fig. 3 is a perspective view of a portion of the switch, switch-stand, and lock, showing the parts on a larger scale. Fig. 4 is a transverse section on the line $z-z$ of Fig. 3. Fig. 5 is a detail perspective view of a low-down or modified form of switch-stand embodying the invention. Fig. 6 is an elevation of a signal mechanism embodying the invention, showing operating mechanism admitting of connection therewith of independent switch-stands. Fig. 7 is an edge view of the mechanism shown in Fig. 6. Fig. 8 is a modified form of switch-stand. Fig. 9 is a detail view of a trip mechanism for sounding an alarm on the train and effecting a setting of the brakes and a shutting off of the motive power, if need be.

Corresponding and like parts are referred to in the following description and indicated in all the views of the drawings by the same reference characters.

The main track is indicated at 1, and the siding or branch at 2, 3 representing the switch-point. The rod 4 for connecting the

switch-point to the operating means may be of usual arrangement and connected with the operating-lever in any ordinary way. As shown, the rod or bar 4 is connected to a crank at the lower end of a vertical shaft 5, having a signal 6 at its upper end and to which the operating-lever is secured, said lever being composed of the parts 7 and 8, which are overlapped at their inner ends and pivotally connected. The outer part 7 of the operating-lever constitutes the handle portion and is adapted to be secured so as to hold the switch when closed, thereby supplementing the action of the lock. The stand 9 has a notch to be engaged by the handle portion 7 when turned downward, as shown most clearly in Fig. 3.

The lock consists of a bar 10 having an end portion extended beneath the movable end of the switch-point 3 and the rail adjacent thereto and having a stop 11 to engage with the switch-point and hold the same when closed or against the adjacent rail. A bell-crank 12, fulcrumed at its elbow to a tie or other support, has its vertical arm connected with, respectively, a distant signal and the co-operating switch-point, whereas its horizontal arm is connected with the lock 10, so as to move simultaneously therewith. A lever 13, fulcrumed intermediate of its ends to a tie or other suitable track-support, has one end connected to the lock 10 and its opposite end pivotally connected with a companion lever 14, likewise pivoted intermediate of its ends and having its outer end connected by rod or bar 15 with the handle portion 7 of the operating-lever, so as to effect a consonance of movement between the lock and signal. A fork 16, pivoted to the upper end of the rod or bar 15, is adapted to embrace the handle portion 7 of the operating-lever to obviate binding when moving the lever, said fork admitting of the operating-lever moving laterally after being turned a distance to clear the engaging portion of the stand 9. When the parts are in the position shown in Fig. 3, the signal is at "safety," but should the switch-point 3 be prevented from any cause closing tight against the main rail the stop or engaging portion of the lock 10 will not engage with the switch-point, so as to hold the same in normal position, and the signal cannot be thrown to "safety," thereby advising the operator that the switch is not properly closed. The rod or bar 15 is supported intermediate

of its ends by means of a bracket 17, which is attached to the stand 9.

In the modified form of switch-stand shown in Fig. 3 the lock 10 is connected by link 18 to one arm of a bell-crank lever 19, the latter being provided with a dog 20 for co-operation with a notched standard 21, by means of which the working parts are held in normal or given position. In this form of switch-stand 10 the switch-point 3 is adapted to be moved by means of a lever 22, which may be connected to the switch-throwing rod or bar 4 in any manner. It is to be understood that when the switch-point is locked the signal cannot 15 be operated, and it is imperative that the switch-point be fully closed before the signal may be thrown from "danger" to "safety." The signal-operating mechanism is connected directly with the lock 10. Hence movement of 20 the lever causes a corresponding movement of the signal, and the operator may be informed of the condition of the switch by observation of the signal. Should anything prevent the closing of the switch-point, the 25 signal cannot be moved to indicate "safety."

It is contemplated to operate the signal from independent switch-stands, and to admit of this result the construction illustrated in Figs. 6 and 7 has been devised. In these 30 figures, 23 represents a flat piece of metal running through a casing or closed metal box 24. Lugs or boxes 25 and 26 show a clear position and said signal 26, as stated, is adapted to be operated by means of two switch-stands 35 independently of each other. When signal is thrown to indicate "danger," lug or dog 25 being connected, as shown, pulls downward the flat piece of metal bar 23, and said lug striking arm 27 throws arm 28 in a diagonal 40 position or opposite side of the casing or box. This is for the purpose that in case both switches and both lugs or dogs 25 pulled down the first switch reversed to normal position has no effect on signal, from the fact 45 that arm 28 being in diagonal position throws lug 25 out of notch 29 in rod or plate 23 and lets it go to the top, where it passes between a spring 30 and the part 23, and when the last switch is placed in normal position said 50 spring pushes said lug in the notch of the part 23. It will be observed that when lug 25 is pushed to the top that the arm 27 and the arm 28 on opposite side of the box are returned to normal position, thereby permitting 55 lug 25 to be engaged with the plate or element 23, whereby the signal may be caused to indicate "safety" or a clear track.

In Fig. 8 is indicated a different form of bracket where the handle portion 7 of the operating-lever operates in. The handle portion 7 of the operating-lever when rotated to open the switch and placed in the notch thereof to hold said switch in position, also enters notch 31 of the bracket 32, so that the 60 downward movement of handle will not in-

terfere with the said clasp or bracket. It will be observed that the provision of the part 32 enables the part 16 to be dispensed with. This part also prevents closing of the switch and locks the same in position without first 70 throwing the signal to "safety." With the open part 16 the operator is enabled to throw the handle portion 7 high enough so it will pass underneath the lower prong of the part 16, thereby permitting the stand to be operated 75 same as though the invention were not applied thereto, the difference being that the signal remains at "danger." This also applies to the modified form of stand indicated in Fig. 5.

The operating-wires 33 are suspended, as indicated at 34, thereby enabling the signal to be operated at a great distance from the switch-stand. A spring-compensator 35 is interposed in the length of each wire 33 to 85 allow for contraction and expansion, the tension of the spring being such as to prevent any slack in the wire and yet prevent operation of the signal should the wire contract under a reduced temperature. A tension device 36 allows proper adjustment of the spring-compensators. It is noted that a D-rail is operated by movement of levers and that the invention may be adapted to low and high 90 stands now in use, thereby obviating the necessity of providing new stands in the installation of the invention on any railway system. 95

At a convenient point in the track a trip mechanism is located to effect a sounding of an alarm on a train to apprise the engineer of 100 impending danger in the event of the danger-signal not being observed either through fog or by oversight. This trip mechanism consists of a bar 37 and trips 38 attached thereto, the trips 38 normally occupying an inoperative position, but which are thrown into a working position when the danger-signal is set. An operating-wire 33 is connected to 105 one arm of a bell-crank 39, the other arm of said bell-crank being attached to the bar 37. 110 When the wire 33 is drawn upon to set the signal to "danger," the bar 37 is at the same time operated and causes the trips 38 to project into the path of an operating device mounted upon the locomotive or other convenient 115 portion of the train, so as to produce a signal and warn the engineer of danger. When the signal returns to "safety," the bar 37 likewise assumes a normal position and causes the trips 38 to be thrown out of action. 120

Having thus described the invention, what is claimed as new is—

1. In a railway-switch, the combination of the switch-point, a bar arranged transversely of the switch and having an end portion extending beneath the switch-point and the rail adjacent thereto and provided with a stop, a bell-crank lever having one arm connected to said bar and its outer arm connected to a signal, and means for operating said 125 130

outer bar to project its stop into or out of the path of the switch-point and to simultaneously operate the signal.

2. In a railway-switch, the combination of a switch-point, a pivoted bar having an end portion extended beneath the switch-point and the rail adjacent thereto and provided with a stop to engage with the switch-point, a bell-crank lever having one arm connected to said bar and the other arm connected with a signal, whereby the latter is simultaneously operated upon actuation of the bar to project its stop into or out of the path of the switch-point, a switch-stand, and connecting means between the operating-lever of the switch-stand and the aforementioned bar.
3. In a railway-switch, the combination of a switch-point, a lock therefor, a bar 15 operatively connected with the said lock, a switch-stand embodying an operating-lever 13, and connecting means between the operating-lever and the bar 15, whereby movement of the lever 13 to effect its release actuates the said lock and further movement of said operating-lever to throw the switch effects disconnection of said lever from the bar 15.

4. In combination, a movable switch-point, a lock therefor, a bar 15, connecting means between said bar and the lock, a switch-stand embodying an operating-lever 30 13, and a fork having swivel connection with the bar 15 and adapted to embrace the movable handle portion of the lever 13, whereby initial movement of the handle portion effects a release of the lock, and whereby a continued movement of the lever 13 disengages it from the swivel-fork.

5. In combination with a switch, a signal and co-operative actuating means for the signal and switch, of a movable element 23, a 40 pair of coöperating dogs 25, springs 30 conjunctively arranged with reference to said dogs, and corresponding pairs of arms 27 and 28, the parts being arranged to admit of independent operation of separate switch-operating mechanisms.

In testimony whereof I affix my signature in presence of two witnesses.
